SASH HANGING DEVICE

Karl O. Gober, Oakland, Calif.

Application April 27, 1939, Serial No. 270,327

2 Claims. (Cl. 16—197)

The invention relates to a counterbalancing device for double-hung window sash.

An object of the invention is to provide an improved arrangement wherein the upper and lower sash of windows are arranged to mutually counterbalance each other through their supported connection by flexible and elastic cord members passing over pulleys mounted on the frames for the sash.

10 Another object is to provide for a controlled stretching of the sash-supporting cord in such a manner that a positive upward pull may be exerted on either of the sash by a downward movement of the other.

15 A further object is to provide a device of the class described wherein the hardware thereof may be installed in connection with present window sash and their frames with particular readiness and without requiring special structures for 20 the sash or frames.

25 The invention possesses other objects and features of advantage, some of which, with the foregoing, will be set forth or be apparent in the following description of a typical embodiment of the invention, and in the accompanying drawings, in which,

30 Figure 1 is an inside face view of a window having its upper and lower sash mutually counterbalanced by the use of the device of present invention, the window casings being omitted, and a portion of the lower sash being shown in section.

35 Figure 2 is a fragmentary inside elevation of the window and sash assembly, with certain parts broken away to show the upper sash in section.

40 Figure 3 is a fragmentary section at 3—3 in Figure 1.

Figure 4 is a section taken on the broken line 4—4 in Figure 1, with the window fully shut.

45 Figures 5 and 6 are views similar to Figure 4 and respectively showing the window partly open from the bottom only as in Figures 1 and 2 and open both top and bottom.

50 Figures 7 and 8 are enlarged perspective views showing the connections between elastic and inelastic portions of the counterbalance connecting cord, a stop means for said cord being shown as operative in Figure 8.

55 Figure 9 is a fragmentary perspective view showing a latch means as operative to secure the two sash against relative movement thereof.

Figure 10 is a vertical section through the structure of Figure 9.

55 Figure 11 is a perspective view of an unmount-

ed connector member for the elastic and inelastic cord portions.

As particularly illustrated, the device of my invention is provided in connection with upper and lower sash 14 and 15 which are provided in a window frame 16 of a usual structure. The window frame opening is defined between mutually parallel side members 17, a top cap member 18, and a sill 19. The sides 17 provide a pair of parallel and upright guideways in which the sash 14 and 15 are slidable for the full height of the window opening, said guideways being defined at opposite sides of beads 21 which extend from the frame sides. The lower sash 15 is disposed in the frame guideway which is inwardly 10 of, the bead 21 whereby the upper sash 14, when raised, may discharge rain therefrom only upon the outer face of the lower sash 14.

As is usual, the lower frame element 22 of the upper sash is provided with an inwardly protruding rib or bead 23 which extends into the space between the two sash and has an upwardly directed face 24 which is complementary to the downwardly directed face 25 of a rib or bead 26 which is provided on the upper frame member 27 of the lower sash 14 and extends into the space between the sash. When the window is fully closed, as in Figures 4 and 9 and 10, the ribs 23 and 26 are cooperative to provide an anti-draft seal between the two sash, while the upper frame element 28 of the sash 14 and the lower frame element 29 of the sash 15 provide air seals at the cap 18 and sill 19 respectively.

50 Grooves 31 and 32 are defined in and along the side frame members 33 and 34 respectively of the sash 14 and 15, corresponding grooves of the two sash being arranged to receive end portions of flexible and longitudinally elastic elements which connect the two sash over pulley units 35 which are mounted at the top of the window 40 frame. Preferably, and as shown, the pulleys 35 are mounted with their wheels 36 in the planes of the corresponding grooves 31 and 32 of the two sash and above the window opening, whereby their presence does not interfere with 45 the normal engagement of the upper sash with the frame cap 18 and they may be concealed.

The wheel 36 of a pulley unit 35 is mounted on an axle 37 which extends between the opposite and mutually parallel sides of a housing or casing 38 for the wheel, and said casing is arranged for its disposal in and through a cross-slot 39 which would be provided in the frame cap 18. As shown, one side of the slot 39 lies in the plane 50 of the inner face of the adjacent frame side 17 55

whereby the installed pulley may be disposed in a plane adjacent said side and coincident with the common plane of the cord-receiving grooves 31 and 32 at the same window side. The pulley unit 35 is preferably so disposed that the bottom of its casing 38 is flush with the lower face of the frame cap 18 whereby to minimize the head room required above said cap while avoiding any alteration of the sash for fitting to the pulley when either sash is fully raised. Also, because no working parts are required beyond the side frame members, the present arrangement is understood to permit the use of a window frame with the widest possible window opening for a given wall opening.

The pulley units 35 may be fixed in their operative position in any suitable manner. As shown, a pulley casing side which is aligned with a frame side 17 is extended downwardly and is arranged to be screwed or nailed to the frame side. Also, the slots 39 are preferably formed for the drive fit of the pulley units 35 therein, as the sole or a partial means to secure the units in place on the window frame. While the present unit 35 comprises a pulley rotatably mounted in a supporting housing, it will be understood that a structure providing an inverted U-bend guideway for the movement of a flexible sash-supporting element around it will serve the present purposes as the operative equivalent thereof in the present combination.

It will now be noted that each flexible sash-supporting member essentially comprises a tension spring 41 and a cord 42 mutually attached by a connector member 43, and respectively comprising longitudinally elastic and inelastic portions of the sash-supporting member. While the spring 41 is shown as comprising a helical coil of spring wire, and the cord 42 is shown as a multi-strand structure of either fibrous material or wire, the spring 41 might comprise a longitudinally stretchable element of rubber or the like composition, while the member 42 might be of a chain or similar structure. Like spring-and-cord assemblies are provided at opposite window sides whereby to divide the sash support and minimize side friction of the sash in their guideways, this being standard practice for double-hung sash.

The length relations of the connected springs 41 and cords 42 are preferably such that the cords engage over the pulley wheels 36 for all relative positions of the supported sash 14 and 15, and the two assemblies may alone support the two sash in counterbalanced relation in which the window opening is at least partly open, as in Figures 1 and 2 and 5 and 6. A full closing of the window opening by the two sash requires a stretching of the spring 41, as is shown in Figure 4, and a suitable catch means is provided for direct coaction between the sash to mutually secure the latter in a usual window-closing relation in which the ribs 23 and 26 of the respective sash are cooperative in the described manner as an air-sealing means between the sash.

As illustrated, the catch means for mutually securing the two sash in window-closing relation comprises a spring-pressed bolt 44 carried in a tubular housing and mounted transversely in the lower sash element 27 to normally extend from the rib 26 of the element for its removable engagement in a socket 45 which is provided in a keeper plate 46 mounted on the outer face of the upper sash member 22 in countersunk relation in its rib portion 23. The plate 46 preferably provides a bevelled approach surface 47

above the socket 45 whereby the bolt may be operative as a spring catch as the sash members 22 and 27 are moved into mutual opposition during a full closing of the window. It will be noted that the installation of the disclosed catch assembly requires only the boring of a hole transversely through the member 27 to receive the housing of the bolt 44 and a cutting out of slots across the sealing ribs of the members 22 and 27 to receive the keeper plate 46 which is mounted 10 on the member 22.

By reference to Figures 7 and 11, it will be seen that the present connector 43 is shaped of a piece of sheet material to define a channel having a longitudinal extension 48 of its bottom portion formed as a hook to engage a terminal hook 49 of the spring 41 for detachably connecting the member and spring. The channel bottom is also provided with a pair of perforations 51 for receiving a bend of the end portion of the cord 42 20 with the cord extremity disposed adjacent the hook end of the connector and within the connector channel, and lateral extensions 52 of the side walls of the connector are provided for folding over and against the cord extremity in the 25 channel to secure the same in place for providing a positive attachment of the connector to the cord.

It will now be noted that each of the side grooves 31 of the upper sash 14 is long enough 30 to fully receive the springs 41 when they are stretched beyond the lengths they must have when the window is fully closed, as in Figure 4, and that the lower spring ends may be anchored by a suitable means at an appropriate point along 35 the groove. In the present case, the sash frames are assumed to be of wood, and the lower spring ends may be secured to the sash sides by nails or staples 53. The side grooves 32 of the lower sash 15 may be relatively short, and knotted cord 40 ends may be fixed in laterally enlarged lower groove ends by the use of a nail or staple 54 engaging them and the sash frame. It is to be understood that the present arrangement of anchorages for the ends of a spring-and-cord tension unit is applicable to all-metal sash which are usually provided with side grooves or channels corresponding to the grooves 31 and 32.

With the spring-and-cord units correspondingly connecting the two sash and the sash otherwise free in their guideways, the sash are arranged to mutually counterbalance each other with the window open to a degree determined by the relative positions of the two sash in the window opening, as is particularly and differently 55 illustrated in Figures 5 and 6. When the lower sash 15 is pulled down to fully close the window, the upper sash 14 will be raised to engage the frame cap 18, and the spring 41 will thereafter be stretched until the window is closed to permit the engagement of the catch bolt 44 in the socket 45, this being the condition shown in Figure 4. A subsequent withdrawal of the bolt 44 from the socket 45 will permit an upward movement of the lower sash upwardly and entirely under the influence of the springs 41 to its position of counterbalancing and without effecting any lowering of the upper sash 14. If a lowering of the upper sash is desired, the lower sash is raised further by hand to permit a corresponding lowering of the upper sash, as is indicated in Figure 6. It will be noted that the present arrangement provides for a maximum opening of the window while the sash are counterbalanced in transverse registration with each other centrally of the window frame opening. Also, and in view of the 75

described action, it will be understood that the spring 41 might be mounted in and attached to the lower sash while the cord 42 is fixed to the upper sash without changing the described operation of the arrangement.

5. Since a sash may stick in its guideway occasionally, means are preferably provided whereby the upper sash 14 may be positively pulled to its fully raised position if the spring tension fails to free and move the lowered sash when the lower sash is pulled down. Accordingly, and as is brought out in Figures 7 and 8, means are preferably provided on the sash which carries the spring 41 to so engage the cord when the spring 10 is stretched slightly beyond its required length for a fully closed condition of the window that the inelastic cord may then provide the sole operative connection of the two sash, and a further lowering of the lower sash will positively urge a raising 15 of the upper sash toward its fully raised position.

20. In the present instance, each cord-engaging means on the sash 14 which carries the springs 44 comprises a plate 56 fixed to the sash across the groove 31 and perforated in the central line 25 of the groove to freely receive the cord 42 therethrough and to have the corresponding connector member 43 engage its under side as a stop to limit the stretching of the spring and provide a direct and inelastic cord connection between the two 30 sash, as may be needed. While the present arrangement is such that a connector 43 provides the cord stop for coaction with the plate 56, it will be understood that a separate member on the cord might provide the stop thereon for engagement with said plate on a sash.

35. From the foregoing description taken in connection with the accompanying drawings, the advantages of the construction and operation of the present sash hanging device will be readily understood by those skilled in the art to which this invention appertains. While I have described the features and principles of operation of a structure which I now consider to be a preferred embodiment of my invention, I desire to have it 40 understood that the showing is primarily illustrative, and that such changes may be made, when desired, as fall within the scope of the following claims.

45. 1. In a window having a frame slidably mounting upper and lower sash for their disposal to co-

5. operatively close the window opening, a pulley mounted at the top of the window frame, a flexible cord looped over said pulley and supportingly connecting said sash in a counterbalanced relation such that the sash are mutually overlapped in the window opening to provide a partly open condition of the window, the portion of said cord 10 between the pulley and its connection to the upper sash including a longitudinally elastic part extending entirely within the confines of the upper sash and the remainder of the cord being relatively inelastic, and stop means cooperative between the upper sash and the cord comprising a removable connector member longitudinally adjustably carried on the inelastic cord portion and 15 lockable thereon in operative position and said removable connector member in operative position positively attached to the elastic portion to thereby connect the inelastic and the elastic cord portions together and a fixed projection on the 20 sash for engagement by the connector member when the elastic portion is stretched to its desired limit.

2. In a window having a frame slidably mounting upper and lower sash for their disposal to co- 25 operatively close the window opening, a pulley mounted at the top of the window frame, a flexible cord looped over said pulley and supportingly connecting said sash in a counterbalanced relation such that the sash are mutually overlapped 30 in the window opening to provide a partly open condition of the window, a portion of said cord between the pulley and its connection to the upper sash including a longitudinally elastic part 35 extending solely within the confines of the upper sash and the remainder of the cord between the pulley and the elastic part being relatively inelastic, and stop means cooperative between the upper sash and cord, comprising a separate member 40 adjustably fixed to the inelastic cord portion at substantially the end thereof removed from the pulley, and said member attached to the elastic cord portion at substantially the end thereof removed from the end connected to the sash, to provide a partially inelastic and elastic cord extending from the pulley to the point of connection to the sash, and a fixed projection on the sash for engagement by the member when the elastic portion 45 is stretched to its desired limit.

KARL O. GOBER. 50
